UNITED STATES PATENT OFFICE.

HJALMAR ELMBLAD, OF CHICAGO, ILLINOIS.

WRITING MACHINE.

Application filed October 23, 1922. Serial No. 596,349.

To all whom it may concern:

Be it known that I, HJALMAR ELMBLAD, a citizen of the United States, and resident of Chicago, in the county of Cook, State 5 of Illinois, have invented new and useful Improvements in a Writing Machine, of which the following is a specification.

This invention relates to a machine especially adapted to selectively print large 10 letters or characters, one at a time, and pertains particularly to the spacing mechanism whereby just spacing may be obtained. The invention disclosed herein pertains to the type of writing machine 15 shown in Patent 1,352,405, granted to me September 7, 1920.

It is the principal object of this invention to provide a spacing mechanism which is simple, compact in structure, and positive 20 in operation. These objects together with other objects and corresponding accomplishments are obtained by means of the embodiment of my invention illustrated in the accompanying drawings, in which:

25 Fig. 1 is a plan view of a complete machine; Fig. 2 is a plan view on an enlarged scale of details of the spacing mechanism; Fig. 3 is a front elevation of a complete machine; Fig. 4 is an enlarged elevation of the 30 mechanism shown in Fig. 2, a vertical section through the table being shown; Fig. 5 is a side elevation of the complete machine; Fig. 6 is a section seen on the line 6—6 of Fig. 2; Fig. 7 is a vertical section on an enlarged scale showing a fragment of the machine as seen on the line 7—7 of Fig. 1; Fig. 8 is a vertical elevation on an enlarged scale of details of the spacing 35 actuating mechanism, parts being in section on a broken line which will be understood from the detailed description; Fig. 9 is a view similar to Fig. 8 showing the actuating mechanism in another position; Fig. 40 10 is a plan view of a fragment of the table showing details of the paper carriage; Fig. 11 is a section as seen on the line 11—11 of Fig. 10; Fig. 12 is a section 45 as seen on the line 12—12 of Fig. 10.

Broadly the machine comprises a wheel 50 carrying type on its periphery, which may be depressed, when the proper type is in position for printing. A carriage for paper is provided with suitable mechanism for advancing the paper under the wheel 55 after type impressions are made.

The table which supports the mechanism

is indicated by A. Mounted upon the table is a head B. The latter supports a type wheel C in such a manner that it may be rotated, depressed and elevated in a vertical plane for making a printed impression. The paper is moved over the table by means of the spacing mechanism indicated generally by D.

Referring more particularly to Figs. 1, 65 3, 5, and 10, the table A comprises a top 14 supported upon sills 15 and 16 which extend from the front to the back of the table. Mounted upon the sides of the table so as to slide thereover are triangular plates 17 70 connected at the front by a cross piece 18 upon which a scale is marked. Rails 19 are secured to the plates 17 and overhang the sides of the table so as to guide the plates in their sliding movement backwardly and 75 forwardly on the table. To prevent displacement of the plates, lugs 20 are secured thereto and engage the sides and bottom of table 14. An adjustable cross bar 21 is secured to the plate by means of bolts and 80 wing nuts indicated by 22. Cross pieces 18 and 21 are grooved, see Fig. 5, to guide and retain the paper therein. Formed in the table at the place where impressions are made, is a recess 23 covered by a housing plate 24 for feed rollers, see Figs. 4 and 6. The housing plate is provided with 85 openings and disposed therein with their peripheries elevated slightly above the surface of the plate are feed rollers 25, these 90 rollers being journaled in the table. The rollers are for the purpose of aiding smooth movement of the paper over the table.

95 Mounted upon the table is the head B for carrying the type wheel and spacing mechanism. This head comprises a hollow upright arm 26 which is provided with a hollow forwardly extending arm 27. Secured to the forward end of the arm 27 and depending therefrom is a plate 28. Secured to the plate at the sides thereof are guide lugs 29, which form ways for a plate 30, to which the type wheel is secured. The type wheel is journaled upon a pintle 31, see Fig. 7, 100 which is fixedly secured to plate 30 and has a stub 32 disposed in the bore of arm 27 of the standard. Engaging the stub 32 and tending to hold the type wheel in its upper position is a leaf spring 33. This spring rests on a fulcrum 34, the rear end thereof 105 being supported in a sleeve 35, which rests against an adjusting screw 36. By adjust-

ing screw 36, the tension of the spring may be adjusted. Slidably mounted in a bore adjacent the forward end of the spring 33 is a pin 37 for engagement by a copy holder 5 later described. Wheel C is journalled upon pintle 31, and key 38 extending through the pintle holds the type wheel against displacement. Secured on the hub of the type wheel is a sleeve 39 having at its 10 outer end a handle 40. The sleeve is held in position by a set screw 41. The type wheel may be rotated and depressed by manipulating the handle 40. On the outer face of the wheel are type bearing characters for printing, and the characters are also marked on the inside of the wheel in corresponding positions. Cut into the rim on the front side of the wheel are guiding and spacing notches, one for each character. These notches are 15 for the purpose of properly guiding and spacing the letters or the characters as they are printed. The spacing as herein shown is not uniform, but varies directly with the width of the characters and is hereafter 20 called just spacing to distinguish from uniform spacing. The operation of the notches in cooperation with the other elements of the spacing mechanism will be described 25 later.

30 Referring particularly to Figs. 2, 3, 4, 6, 7, 8, and 9, a frame 42 is secured to plate 28. This frame has forwardly extending arms 43 and 44 connected by a cross piece 45. An extension 46 of the frame disposed to the 35 rear, is preferably made integral therewith, with a rod 47 serving as a slide for a bridge 48 mounted thereon. The bridge is provided with a roller 49 and is fixed to an L shaped arm 50 by means of a set screw 51.

40 Secured to one side of extension 46 and to a block 52 fixed on the end of arm 50 is a tension spring 53. The tension spring tends to move arm 50 outwardly. The forward end of arm 50 is provided with a collar 54 slidably mounted upon a rod 55. A nut 56 is mounted upon rod 55 to abut the collar. Rod 55 has secured thereto a collar 57, and disposed between collars 54 and 57 upon the rod is a spring 58. By this means, the rod 55 is yieldingly secured to the arm 50. Rod 55 is slidably supported at each end upon guides 59 and 60 which ride upon bar 45.

45 A frame 61 consisting of a plate and brackets is slidably mounted on bar 45, straps 62 holding it in position. Disposed below bar 45 is a paper feed dog 63. It comprises a bar having teeth on its lower face to engage the paper. It is so mounted that it may be moved up or down. A lever arm 64 is pivotally secured thereto as indicated by 65. Arm 64 is pivotally mounted upon the frame 61 at pivot point 66. By swinging arm 64, the dog 63 may be moved to or from the table. A catch 67 is pivotally secured to arm 64 and may engage a

notch 68 on the top of frame 61. When the catch is disposed in notch 68 it maintains arm 64 in such position that the feed dog 63 is held out of contact with the paper. Slidably mounted on rod 55 and secured to plate 45 is a release 69 disposed to engage catch 67 and release it from the notch 68. A bail 70 on rod 55 is engaged with a pin 71 on arm 64 so that movement of the rod causes the arm 64 to be rocked and feed dog 63 to be raised or lowered. A spring 72 is secured at one end to lever 64 and at the other to frame 61. This spring tends to hold arm 64 in such position that feed dog 63 is depressed. A retarding dog 73 is pivoted on bar 45. It has a collar 74 secured thereto and a spring 75 which presses the dog against the paper. An elevation 76 on plate 24 is in registry with the retarding arm, thereby providing a better grip on the paper. Disposed on the table to form the impression surface is a pad 77 preferably of rubber or felt glued on a steel plate. The lower end of arm 64 is disposed under retarding dog 73 so that when the feed dog 63 is elevated by the arm 64, retarding dog 73 will also be elevated. This position of the parts is shown in full lines in Fig. 4 and allows free movement of the paper. The dotted lines show the dogs in action on the paper.

50 A spacing hook 78 measures the distance the paper is to be moved for each letter. Hook 78 rides on the outer face of the wheel C and arrests motion of frame 61 by engaging in one of the notches on the wheel. Hook 78 is pivoted on frame 61. Its pivot pin has an arm 79 fixed thereto which is secured at one end by a spring 80 to the frame. The spring 80 through arm 79 raises hook 78 and keeps an upward tension on it at all times. A lever handle 81 is pivoted on bar 45 and engages strap 60. Spring 82 tends to maintain the handle out of engagement with the strap. By swinging handle 81, frame 61 may be moved independently of the type wheel, rod 55 sliding through collar 54 which remains stationary. When printing, forward motion of frame 61 is derived from spring 53 through rod 50. Arm 83 is pivoted on arm 27 of head B, as indicated by 84. The upper end thereof has a roller 85 riding on plate 30. The lower end engages roller 49 on frame D. Arm 83 brings the frame D back to its original position and prevents too rapid forward movement of frame 61.

55 A guide pin 86 is fixed to bar 45 and passes through the notch of the character being printed. This exactly locates each character. A lever 87 is pivoted to frame D at 88. Mounted on lever 87 by a loose pivot pin 89 is a clamping dog 90. Dog 90 is mounted on a rod 91 which is secured at its front end to scale 18, forming a part of the paper carriage. Dog 90 has apertures for the rod of such diameter that the dog may

be rocked to the position shown in dotted lines in Fig. 11. In this position, it grips rod 81, and the paper carriage may thereby be moved a line. A tube 92 secured to table 5 A has rod 81 telescoping in it and guides the latter in its movement.

Inking rollers 93 bearing against the face of the type are mounted in a housing supported upon an arm 94. Any other suitable 10 means for inking may be employed. Frisks 95 and 96 prevent type adjacent to the one to be impressed from printing.

The type wheel may be removed and a wheel having a different style of type installed. This is accomplished by removing 15 set screw 41 and slipping sleeve 39 and handle 40 from the hub. Key 38 may then be removed. To dispose and hold the type wheel in such position that it may clear the 20 inking rollers and spacing mechanism, copy holder arm 97 is swung downwardly to engage plunger pin 37 which acts upon spring 33 depressing the wheel to the position shown in dotted lines in Fig. 7 permitting 25 the wheel to be slipped from pintle 31.

The handle of arm 64 is moved to the right so as to lift feed dog 63 from rollers 25 and permit catch 67 to drop into notch 68, thereby holding the dog in its upper position. 30 The sheet of paper to be printed upon is placed with the lower edge in the groove of cross-piece 18 of the paper carriage and the upper edge in the groove of cross-bar 21. The latter is adjusted as to position by 35 loosening screws 22 and moving the bar 21 to the proper position, then tightening the screws. The entire paper carriage, including plate 17 is then moved so that the letters on the type wheel are at the proper line 40 positions on the paper. The paper is then slipped along the cross-bars until in position for printing the first letter or character. Type wheel C is rotated to bring the letter to be printed and its notch in registry with 45 pin 86, and the wheel is then depressed thereby printing the desired letter. On depression of the type wheel, plate 30 is moved downwardly, see Fig. 9. This causes the lower end of arm 83 to swing outwardly and 50 to permit bridge 48 to follow the arm to the right. The bridge being fixed to arm 50 is caused to move therewith by reason of the tension of spring 53. When arm 50 is moved to the right, it moves rod 55 to the 55 right, and drags frame 61 to the right by reason of the connection of the rod through the bail 70 and pin 71. Catch 67 is engaged by release 69 which is fastened to bar 45, and is raised from notch 68. The frame is moved 60 to the right until hook 78 engages the notch on the wheel in registry with the character next to the right from the one just printed. This limits the movement of the frame. The 65 distance between notches on successive letters or characters measured in a clockwise

direction about the type wheel is arranged according to just spacing. Upon releasing pressure on the handle 40 of the type wheel, spring 33 moves it upwardly. This causes plate 30 to be moved upwardly, and arms 83 70 is rocked into the position shown in Fig. 8. This causes bridge 48 to be moved to the left and likewise rods 50 and 55. Bail 70 on rod 55 first rocks arm 64 and moves feed dog 63 75 against the paper resting on rollers 25, and further swinging of the arm 64 is inhibited by reason of dog 63 resting against the paper. Further movement of rod 55 to the left causes the frame 61 to be dragged along 80 by reason of the connection with the rod through bail 70 and pin 71. The result is that the paper is moved by feed dog 63, which presses thereagainst and is dragged to the left a distance equal to just spacing. The wheel is then rotated to position for print- 85 ing the next letter.

Suppose it is desired to space between characters, the handle of lever 81 is grasped and rocked to the left. The lower arm of the lever presses against guide 60 and moves 90 rod 55. The latter slides in collar 54 against the action of spring 58. The frame 61 is then moved to the right in the manner before described. Spring 58 returns rod 55 and the paper thereby moves one space. To 95 move the paper to a new printing line, lever 64 is moved to raise dog 63 from the paper, catch 67 dropping into notch 68. Handle 87 is then pushed from the operator, rocking dog 90 so as to grip rod 91 and move 100 the paper carriage away from the operator.

What I claim is:

1. In a printing machine, the combination of a platen for paper to be printed; a rotatable type wheel movable so as to be 105 depressed and engage said paper, said wheel having spacing notches on the rim thereof corresponding to just spacing; a mechanical movement operated by elevation and depression of said wheel to rock a lever; a bridge 110 engaged by said lever and having resilient means tending to move it in a forward direction, said lever being disposed to move it in a return direction against the tension of said resilient means; a rod secured to said bridge by resilient means permitting movement with respect thereto in a forward direction and restraining it against the movement relative thereto in a return direction; a slidable frame; a hook on said 115 frame disposed to engage a notch on said wheel when the latter is in depressed position; a feed lever pivoted on said frame and having a depressible feed dog; resilient means tending to elevate said dog; means securing said feed lever to said rod so as to initially rock the latter and to move said frame; and manually operable means to move said rod independently of said bridge. 120

2. In a printing machine, the combination 125

of a platen for paper to be printed; a rotatable type wheel movable so as to be depressed and engage said paper, said wheel having spacing notches on the rim thereof corresponding to just spacing; a mechanical movement operated by elevation and depression of said wheel to rock a lever; a bridge engaged by said lever and having resilient means tending to move it in forward direction, said lever being disposed to move it in a return direction against the tension of said resilient means; a rod secured to said bridge by resilient means permitting movement with respect thereto in a forward direction and restraining it against the movement relative thereto in a return direction; a slidable frame; a hook on said frame disposed to engage a notch on said wheel when the latter is in depressed position; a feed lever pivoted on said frame and having a depressible feed dog; resilient means tending to elevate said dog; and means securing said feed lever to said rod so as to initially rock the latter and to move said frame.

3. In a printing machine, the combination of a platen for paper to be printed; a rotatable type wheel movable so as to be depressed and engage said paper, said wheel having spacing notches on the rim thereof corresponding to just spacing; a mechanical movement operated by elevation and depression of said wheel to rock a lever; a bridge engaged by said lever and having resilient means tending to move it in a forward direction, said lever being disposed to move it in a return direction against the tension of said resilient means; a rod secured to said bridge so as to be moved thereby; a slidable frame; a hook on said frame disposed to engage a notch on said wheel when the latter is in depressed position; a feed lever pivoted on said frame and having a depressible feed dog; resilient means tending to elevate said dog; means securing said feed lever to said rod so as to initially rock the latter and to move said frame;

4. In a printing machine, the combination of a platen for paper to be printed; a rotatable type wheel movable so as to be depressed and engage said paper, said wheel having spacing notches on the rim thereof corresponding to just spacing; means operated by elevation and depression of said wheel to reciprocate a rod; a slidable frame; a hook on said frame disposed to engage a notch on said wheel when the latter is in depressed position; a feed lever pivoted on said frame and having a depressible feed dog; and resilient means tending to elevate said dog; means securing said feed lever to said rod so as to rock the latter and to move said frame.

5. In a printing machine, the combination of a platen for paper to be printed upon;

a rotatable type wheel movable so as to be depressed and to engage said paper, said wheel having spacing notches on the rim thereof corresponding to just spacing; a frame movable in the direction of the line to be printed; a hook on said frame disposed to engage a notch on said wheel when the latter is in depressed position; means to move said frame in a forward direction operated by depression of said wheel, said movement being limited by said hook; means to return said frame upon elevation of said wheel; a feed dog for engaging said paper movably mounted on said frame to be pressed against said paper and normally held out of engagement therewith; and means to depress said feed dog upon initial return movement of said frame.

6. In a printing machine, the combination of a platen for paper to be printed upon; a rotatable type wheel movable so as to be depressed and to engage said paper, said wheel having spacing notches on the rim thereof corresponding to just spacing; a frame movable in the direction of the line to be printed means mounted on said frame disposed to engage a notch on said wheel when the latter is in depressed position and to limit forward movement of said frame; means to move said frame in a forward direction operated by depression of said wheel; a feed dog for engaging said paper movably mounted on said frame to be pressed against said paper and normally held out of engagement therewith; and means to depress said feed dog upon initial return movement of said frame.

7. In a printing machine, the combination of a platen for paper to be printed upon; a rotatable type wheel movable so as to be depressed and to engage said paper, said wheel having spacing notches on the rim thereof corresponding to just spacing; a mounting comprising a hook movable in the direction of the line to be printed and disposed to engage a notch on said wheel when the latter is in depressed position and a feed dog to engage said paper; means to move said mounting in a forward direction operated by depression of said wheel, said movement being limited by said hook; and means to return said mounting upon elevation of said wheel.

8. In a printing machine, the combination of a platen for paper to be printed upon; a type carrier having type in a line and linearly movable so as to bring a character into printing position and depressible to engage said paper, said carrier having spacing notches on the edge thereof corresponding to just spacing; a frame movable in the direction of the line to be printed; a hook on said frame disposed to engage a notch on said carrier when the latter is in depressed position; means to move said frame in a for-

- ward direction operated by depression of said carrier, said movement being limited by said hook; means to return said frame upon elevation of said carrier; a feed dog for en-
5 gaging said paper movably mounted on said frame to be pressed against said paper and normally held out of engagement therewith; and means to depress said feed dog upon initial return movement of said frame.
- 10 9. In a printing machine, the combination of a platen for paper to be printed upon; a carrier having type in a line and lineally movable so as to bring a character into printing position and depressible to engage said paper. said carrier having spacing notches on the edge thereof corresponding to just spacing; a frame movable in the direction of the line to be printed; means mounted on said frame disposed to engage a notch
15 on said carrier when the latter is in depressed position and to limit forward movement of said frame; means to move said frame in a forward direction operated by depression of said carrier; means to return said frame upon elevation of said carrier; a feed dog for engaging said paper movably
- mounted on said frame to be pressed against said paper and normally held out of engagement therewith; and means to depress said feed dog upon initial return movement of 30 said frame.
10. In a printing machine, the combination of a platen for paper to be printed upon; a carrier having type arranged in a line and lineally movable so as to bring a 35 character into printing position and depressible to engage said paper, said carrier having spacing notches on the edge thereof corresponding to just spacing; a mounting comprising a hook movable in the direction of 40 the line to be printed and disposed to engage a notch on said carrier when the latter is in depressed position and a feed dog to engage said paper; means to move said mounting in a forward direction operated by depression 45 of said carrier, said movement being limited by said hook; and means to return said mounting upon elevation of said carrier.

In witness that I claim the foregoing I have hereunto subscribed my name this 24th 50 day of May, 1922.

HJALMAR ELMBLAD.
